COATING APPARATUS

Daniel Anthony Scarnegie, Peabody, Mass., assignor to United Shoe Machinery Corporation, Paterson, N. J., a corporation of New Jersey

Application February 16, 1932, Serial No. 593,379

32 Claims. (Cl. 12—80)

My invention relates to apparatus by which a coating of a fluid substance, such as cement, may be applied to work-pieces, it being particularly adapted for thus coating articles beveled at their edges, as is the case with rubber soles of the rolled-edge type. In the manufacture of rubber footwear in which the edges of the soles are rounded outwardly from the tread-surface upon the shoe-top, said soles are cut with an inside 5 bevel, the margins being inclined from the tread-surface upwardly and inwardly. When a sole of this character is cemented to the top, the coating of adhesive must be applied both to the plane inner surface, which is to be attached to the shoe-bottom, and to the beveled edge which is to be turned up and secured to furnish the rolled edge. An object of the present invention is to provide 10 for the application to such work of a substantially uniform coating of the adhesive over both the plane surface and its longitudinally curved and transversely inclined edge, without overrunning upon the opposite side of the work which is to be exposed. It is to be understood, however, that in some aspects my invention is not limited to means 15 for operating upon beveled articles, it having utility in other connections.

As a feature of the invention, there is combined with a receptacle for a coating substance an applying member movable in the receptacle and arranged for contact with a substantially plane surface of an article to be coated, together with a second movable member arranged for contact with the beveled edge of the article. The first of these members may be a rigid roll, and the second 20 is shown as a brush. I preferably move the secondary or auxiliary member transversely of the path of advance of the articles, it acting simultaneously upon the beveled edge at the opposite sides. As illustrated, an endless, flexible member carries groups of brush-fibers or other coating-applying means, and travels across the work. In this way, regardless of whether or not other applying means has acted, the coating substance 25 may be wiped across the entire article, a sole thus receiving the application by members traveling over it and against its inclined edges in opposite directions and insuring the coating of said edges throughout the entire periphery. The secondary applying member preferably receives its 30 supply of the coating substance from the primary member. The transversely movable member just referred to may operate in a secondary receptacle, to which the coating substance is delivered from the receptacle of the primary member. Another form of my invention may be em-

ployed, in which the secondary applying member, shown as a rotatable brush, contacts with the coating substance upon the primary applying member. In this latter organization, the yieldable brush so adapts itself to the contour 5 of the article to be coated that it will operate upon the inclined surfaces which the primary member, this best having a rigid applying surface, cannot reach. Whatever form the applying member may assume, I prefer to associate with it a 10 rotatable feed member provided with projections spaced circumferentially and longitudinally of the axis, these projections being conveniently upon a series of star-wheels. Such toothed feeding means may be caused to positively engage and 15 advance the work whatever the direction of movement of the applying member, while the longitudinal spacing of the wheels allows the irregular surfaces to be coated to be more effectively forced into the yieldable coating member. 20

As another feature of the invention, I arrange to actuate the coating-applying member in opposite directions, there being means for moving it and means for reversing the movement at the will of the operator. The transversely movable member, previously referred to, may thus be caused 25 to travel either in one direction or the other across the work, and thus neutralize any tendency to set the applying fibers at an angle in their carrying means, due to the drag upon the contacting surface, or to wear them irregularly. The rotatable applying member, by its reversal, will either more effectively apply the coating substance when it turns against the advancing work in operating upon beveled articles, or will remove 30 resistance to the advance of the work when only plane-surfaces are being coated and the reverse action is unnecessary. In either case, a member controllable by the operator may be utilized to 35 shift the gearing to produce the two effects. 40

In the accompanying drawings are illustrated 45 an embodiment of my invention and a modification thereof,

Fig. 1 being a broken side elevation of my improved apparatus in its preferred form;

Fig. 2, a top plan view of the delivery-end thereof;

Fig. 3, a transverse vertical section on the line III—III of Fig. 2;

Fig. 4, a fragmentary section on the line IV—IV 50 of Fig. 3;

Fig. 4^a is a vertical section, on a larger scale, to show the construction of the endless chain brush; 55

Fig. 5, a detail in broken side elevation of the clutch mechanism of the preceding figures;

Fig. 6, a similar view, particularly showing the shaft of said clutch mechanism;

5 Fig. 7, a perspective view of a portion of a modified form of the apparatus, employing a rotatable brush;

Fig. 8, a broken top plan view of the gear-shifting mechanism of the apparatus of Fig. 7;

10 Fig. 9, a vertical sectional detail of the brush of Fig. 7 with its associated feed-wheel, operating on a sole having an inside bevel; and

Fig. 10, a like view, illustrating the operation on an outside-bevel sole.

15 Referring to Figs. 1 to 6, the base of the apparatus is shown as furnished by a receptacle 10 for cement or other coating substance, in which receptacle is mounted an applying roll 12, which may be of metal with a nurled or pocketed surface to raise the adhesive and deliver it to the work, this roll being rotatable about a horizontal axis. The roll is driven in the direction of the arrow in Fig. 1 from a gear 14 upon a main power-shaft 16 through an idle gear 18 and a gear 20 upon the roll-shaft. Pivoted upon studs 22 extending inwardly from brackets 24 rising from the receptacle, are arms 26, 26 carrying between them, preferably rotatable upon universal joints 28 (Fig. 2), a driven feed- and pressure-roll 30 co-operating with the applying roll 12 and having a roughened work-engaging surface. The roll 30 is rotated oppositely to the roll 12, acting therewith to advance the work, by a gear 32 (Fig. 1) fast upon the shaft 22 and meshing with the gear 14, and sprocket-gearing 34 uniting the last-mentioned shaft to the roll 30. To permit this roll to yield under the influence of the work as it passes beneath it, springs 36, adjustable as to tension, connect the arms 26 to the brackets 24, 40 and contact-screws 28, threaded through the brackets and engaging the arms, determine the normal position of the roll. In the arms 26 (Fig. 1), vertical slots are shown, in which are loosely mounted the journals of a cleaning roll 40, which rests upon the roll 30 and serves to remove therefrom any adhesive which may gather upon it. The soles or other work-pieces are introduced between the rolls 12 and 30 by horizontal feed-chains 42 operating over a series of spaced sprocket-wheels 44, the shafts of which are journaled in a rearward extension 46 projecting from the receptacle. The forward sprocket-shaft is rotated from a gear 47 upon the shaft of roll 12 through an idle gear 48 and a pinion 49. It will be assumed that soles S, which are to form rolled edges and have their beveled edges x down for coating their lower sides opposite the tread-surfaces, are brought into the machine by the chains 42 and enter, with their longitudinal axes in the direction of advance, between the rolls 12 and 30. The roll 12, against which each sole is pressed by the roll 30, and with the amount of cement which it carries governed by a scraper adjustable upon the receptacle by a hand-wheel 50 (Fig. 1), applies to the inner plane surface y a coating of cement from the receptacle, the edges x receiving little or none of the coating. Up to this point, the illustrated machine is substantially like that shown in Letters Patent of the United States No. 1,849,302, granted March 15, 1932, upon the application of F. D. Kinney. The sole then emerges from between the rolls 12 and 30 to receive the action of a mechanism M, which more essentially constitutes my invention.

Secured across the top of the receptacle, in ad-

vance of the roll 12, is a mounting bar 60 having, rising from its extremities, portions 62 (Figs. 1 and 3). Adjustably fixed to the rear side of the bar by slot-and-screw connections 64 is a toothed scraper 66 (Figs. 2 and 4) extending into close proximity to the surface of the roll 12 to separate the coated soles therefrom and direct them to the mechanism M. Mounted upon or formed integrally with the bar 60 is an elongated receptacle or trough 68, which at the bottom is slotted on the side toward the roll 12 and has along the slot a lip 70 (Fig. 4) situated sufficiently near the surface of the roll to remove cement therefrom, this being forced by the rotation of said roll into the interior of the trough. Slot-and-screw connections 72 between the bar 60 and the receptacle allow the correct cement-gathering relation to be established between the trough and roll. When the trough has become full, the excess of cement overflows at 74 through a slot in the rear wall, being discharged upon the primary roll 12 and maintaining a constant level within the trough. This trough 68 is shown as narrow between its inner side-walls for a considerable portion of its length, but with circular enlargements at its ends, in which are fixed vertical spindles 76 and 78 (Fig. 3). About the spindle 76 rotates a sprocket-wheel 80, while the spindle 78 is surrounded by a sleeve 82 carrying a sprocket-wheel 84. Operating over the two sprockets is a chain 86, which may be of the roller type, the links being joined by rotatable tubular studs 88. Each stud serves as a holder, carrying an upwardly extending brush consisting of a tuft or group of fibers 90. On account of the rotation of the studs, the relation of the fibers about their axes may change and thus compensate for wear and lateral deflection. The chain may be guided at its outer sides by contact with steel bars 92 (Fig. 4) set horizontally in the trough-walls. By journaling the spindle 76 in a bracket 89 secured to the top of one of the bar portions 62 and adjustable by an eccentric 91 the tension of the chain may be altered. The ends of the trough above the sprocket-wheels 80 and 84 are closed by horizontal walls 94 (Fig. 3), in proximity to the under sides of which the ends of the brushes travel. These brush-ends lie above the level of the cement in the trough and receive the adhesive, partly by capillary action from the body in the trough, and partly by wiping along the accumulation upon the walls 94, where it is smeared during the operation of this secondary coating mechanism. The mechanism provides, therefore, a bundle-like endless, work-coating member with opposed elongated side portions constituting runs each of which is provided with individual flexible applying elements or brush units movable transversely of the path of movement of a piece of work. The ends of the individual brushes project into the path of the advancing soles, which are urged down upon them by a series of feeding and pressure members in the form of toothed disks or star-wheels 96. These wheels are spaced from one another longitudinally of a shaft 98 journaled transversely of the path of the work upon a yoke 100. The yoke is pivoted upon studs 101 (Fig. 2), 103 (Fig. 1) upon an extension 108 (Fig. 2) projecting from the receptacle 10, and has articulated to it a 70 forwardly extending U-shaped link 102 with its mid-portion movable between opposite nuts 104, 104 upon a screw 105 threaded horizontally through the center of a bridge 106 joining the sides of the extension 108. By a correct adjust- 75

ment of the nuts 104, the yoke 100 is tilted on the studs 101, 103 and the relation of the star-wheels 96 to the ends of the brushes may be made such as to insure the forcing of the soles into the yieldable fibers 90 sufficiently to produce an application of the cement to the entire beveled edge x .

The wheels 96 are rotated in the same direction as the roll 30 and at the same peripheral speed, to receive the soles from the applying roll 12 and 10 advance them across the brushes. At the same time, the sprocket-wheels 80 and 84 are driven to cause the travel of the chain 86 and the movement of the brushes 90 across the soles. This 15 travel of the chain may be reversed to produce a bending of the fibers in opposite directions, to better distribute the wear and overcome the tendency to permanent set of the fibers in one direction. The gearing for driving the elements of the 20 secondary mechanism M is preferably as follows: The gear 47 upon the shaft of the roll 12 meshes with an idle gear 122 rotatable upon the receptacle 10, this idle gear turning a pinion 124 upon a short shaft 126 to which said pinion is 25 attached. The shaft 126 is journaled in a bracket 127 rising from the side of the receptacle. Mov- 30 able longitudinally of this shaft is a clutch member 128 (Figs. 3, 5 and 6), which is secured to a pin 129 slideable in a recess in the outer end of the shaft 126. To the end of this pin 129 is secured 35 a handle 130. This handle may be shifted to compel to turn with the shaft 126 either a sprocket-wheel 133 or a gear 134. The former is joined by a chain 136 to a sprocket-wheel 138 fixed to a shaft 149 rotatable in the upper portion of the bracket 127, while the gear 134 meshes with a pinion 142 also fast upon the shaft 140. At its inner extremity, this shaft 140 carries a bevel- 40 pinion 144, which engages a like pinion upon the sleeve 82 of the sprocket-wheel 84 bearing the brush-chain 86. It will be evident that the shaft 140 will be turned in one direction or the other, depending upon whether the sprocket-wheel 138 or the gear 134 is coupled by the clutch member 128 to rotate with the shaft 126, and, therefore, 45 the sprocket-wheel 84 may similarly be oppositely rotated. Thus the operator may select the direction in which it is desired the brushes shall travel, and if the fibers become worn at one side or bent over in one direction, the movement may be 50 reversed to produce the opposite and corrective effect.

To turn the star-wheels 96 in the same direction as the roll 30, and to also effect the removal of the coated soles from the mechanism M, the 55 inner end of the extension 108 has journaled horizontally in it a shaft 150 (Fig. 1) carrying a fast pinion 132 rotatable by the idle gear 122. Sprocket-gearing 154 turns an intermediate pinion 156 (Figs. 1 and 2) secured to the pivot 163 (Fig. 1) and rotatable at the top of the bracket 127, and this pinion, in turn, imparts rotation to the star-wheels through a gear 158 secured to their shaft 98, the movement being anticlockwise, as viewed in Fig. 1. This advances the coated 60 work upon delivery-chains 160 (Fig. 2) running over sprocket-wheels 162 upon the shaft 150 and on a parallel shaft 164 at the forward extremity of the extension 108. Sprocket-gearing 166 may join the shafts 150 and 164 to cause them to 65 rotate together.

In using the apparatus, beveled-edge soles S, with the inclined portions x down, are placed upon the feed-chains 42 and by them introduced 70 between the primary applying roll 12 and the co-operating pressure- and feed-roll 30. Cement

raised by the former roll from the receptacle 10 is applied to the plane surface y of each sole, which is then forwarded between the auxiliary brushes 90 and the star-wheels 96. The brushes are constantly supplied with cement taken from the roll 12 by the opening in the trough 68 in which they run. The star wheels 96, by the engagement of their projections, feed the sole forward at the same rate as it was delivered by the primary mechanism, simultaneously forcing it down at 10 spaced points into the brush-fibers. These, traveling transversely in both directions across the sole, wipe at one run of the chain across the sole in one direction, and at the other run in the opposite direction, these movements being effective to apply the cement to the opposite beveled portions, both as the brushes approach and leave the sole. This is as completely accomplished at the ends of the soles as at the sides. Because the brushes are supplied with a comparatively 15 limited quantity of cement, they do not tend to cause it to pass over the sole edge to the surface which is to be exposed in the finished shoe, as might be the case were an effort made to effect the application by the primary member 12 only. 20 The travel of the brushes across the plane surface y also serves to distribute the cement received from the primary roll 12. The rate of movement of the brushes as compared with the advance of the sole is such that said brushes will have ample 25 time for contact with every portion of the edge. If, for reason of continued contact of one side of the brushes 90 upon the soles, they become so worn or deflected as to work less well, this may be corrected by shifting the driving gearing 30 by the handle 130, thus reversing the direction of brush-travel.

In Figs. 7 to 10 appears a form m of the secondary coating mechanism, in which, for the bodily movable brushes 90, a rotatable brush 170 40 is substituted. This latter brush has its shaft 172 so journaled in brackets rising from the extension 108 that the ends of its fibers are close to the surface of the roll 12. From this roll it receives the coating substance which it is to 45 apply, this relation being variable, to cause the proper amount to be taken, by changing the angle of the extension 108. This appears as pivoted at 174 on the receptacle 10 and has an arm 175 beside the wall of said receptacle, to which 50 it is joined by a slot-and-screw connection 176.

As in the previous instance, means is provided for reversing the direction of movement of the brush, though here the function is rather to adapt the mechanism to operate to the best advantage 55 upon soles or other work differing in character from the rolled-edge soles best coated by the mechanism M. For example, it may be desired to employ the apparatus for coating straight-edge soles, such as is shown at s in Fig. 10, and 60 in which the bevel x is outside, or from the tread-surface outwardly and upwardly. This surface is not to be coated, the application in this case being only to a plane surface y which is to be attached both to the shoe-bottom and the adjacent portion of the top. When such work is to be operated upon, the brush 170 simply supplements the action of the roll 12. If the brush 170 were to be called upon to coat the beveled portion of a rolled-edge sole (Fig. 9), it would act 70 most effectively if it were rotated in a direction opposite to that of the roll 12, the resistance offered by the work to the movement of its fibers causing it to better engage the inclined surface. But with the straight-edge sole, such reverse 75

movement would have no utility and would simply unnecessarily resist the travel of the work. Consequently, in the latter instance, the brush 170 is best rotated in the same direction as the roll 12. In this embodiment of the invention, this reverse movement may be effected as best shown in Fig. 8. The gear 47 upon the shaft of the roll 12 meshes as before with the idle gear 122, and the latter engages a pinion 180 fixed to a sleeve 182 turning upon the brush-shaft 172. Splined upon said shaft is a pinion 184, and this and the adjacent extremity of the sleeve have co-operating clutch-portions 186. With the pinion 184 meshes a gear 188, which may either turn loosely upon a shaft 190 rotatable parallel to the shaft 172 or may be clutched to it by engaging portions 192. The shaft 190 is rotated oppositely to the shaft 172 by a pinion 194 engaging the gear 122. The pinion 184 and the gear 188 are arranged to be moved simultaneously in opposite directions, to produce engagement of either the clutch 186 or clutch 192, by a lever 196 fulcrumed upon the extension 108 and having projections 198 entering grooves in the hubs of the pinion 184 and gear 188. The lever may be swung in either direction to produce the desired engagement by a handle 200 secured to its fulcrum-pin. As illustrated in full lines in Fig. 8, the clutch 192 is engaged, and rotation is imparted to the brush 170 to move its fibers engaging the work oppositely to the direction of advance. This, as already pointed out, is efficient in coating the beveled edge. As appears in dotted lines in Fig. 8, the clutch 186 is engaged, and the work-engaging surface of the brush is traveling with the work, to some extent supplementing the applying action of the roll 12 and yet offering no resistance to advance.

In this arrangement, the shaft 98 of the star-wheels 96 may be journaled in a yoke 201 pivoted upon a shaft 204 and an opposite pin in the extension 108 and the yoke 201 is adjustable in a manner similar to the yoke 100 in the organization just described and for a like purpose. In the form now being considered, however, the star-wheels are best raised out of engagement with the work when straight-edge soles are being operated upon. Rotation may be imparted to the shaft 98 from the sleeve 182 by way of sprocket-gearing 202, the shaft 204 and spur-gearing 206. The shaft 150 of the delivery-chains 160 is shown as driven by sprocket-gearing 208 from the shaft 190.

Having described my invention, what I claim as new and desire to secure by Letters Patent of the United States is:

1. In an apparatus for coating articles having a substantially plane surface, an opposite surface, and an interconnecting beveled edge, a receptacle for a coating substance, a member movable in the receptacle and arranged for contact with the plane surface of an article, and a second movable applying member arranged on the same side of the article as said first member for contact with the beveled edge of said article, which edge connects the opposite surfaces of the article.

2. In an apparatus for coating articles having a substantially plane surface, an opposite surface, and an interconnecting beveled edge, a receptacle for a coating substance, a rotatable rigid applying roll receiving the coating substance from the receptacle and arranged for contact with the plane surface of an article, and a movable applying member constructed and arranged to contact with the same plane surface and to yield to en-

gage the interconnecting beveled edge of the article extending from said plane surface to the opposite surface.

3. In an apparatus for cementing shoe-soles having a substantially plane surface and a beveled edge, a cement-receptacle, an applying roll rotatable in the receptacle and arranged for contact with the plane surface of a sole, and a yieldable member constructed and arranged for contact with the plane sole-surface and to yield to produce engagement with the beveled edge of the sole, said yieldable member receiving cement from the roll.

4. In an apparatus for cementing shoe-soles having a plane surface and a beveled edge, a cement-receptacle, an applying roll rotatable in the receptacle and arranged for contact with the plane surface of a sole, and a movable applying member receiving cement from the surface of the roll at a level below the point of contact of said roll with the sole, said applying member being arranged for contact with the beveled edge of the sole.

◆ 5. In a coating-applying apparatus, a receptacle for a coating substance, a work-contacting applying member above said receptacle rotatable to dip in the coating substance therein, and a second work-contacting applying member situated in proximity to a downgoing part of the first-mentioned member above the substance in the receptacle and arranged to receive portions of coating substance therefrom which have not been applied to the work.

6. In a coating-applying apparatus, a primary receptacle for a coating substance, an applying member movable in the primary receptacle, a secondary receptacle arranged to receive the coating substance from the applying member supplied by the primary receptacle, and an applying member movable in the secondary receptacle.

7. In a coating-applying apparatus, a primary receptacle for a coating substance, an applying member movable in the primary receptacle, a secondary receptacle arranged to scrape unused portions of the coating substance from the applying member supplied by the primary receptacle, and a coating-applying brush traveling in the secondary receptacle.

8. In a coating-applying apparatus, a primary receptacle for a coating substance, an applying roll rotatable in the primary receptacle, a secondary receptacle having an opening co-operating with the roll to receive the coating substance therefrom, and an applying member movable in the secondary receptacle.

9. In a coating-applying apparatus, a primary receptacle for a coating substance, an applying roll rotatable in the primary receptacle, a secondary receptacle having an opening co-operating with the roll to receive the coating substance therefrom and being arranged to deliver its overflow back to the roll, and an applying member movable in the secondary receptacle.

10. In a coating-applying apparatus, a primary receptacle for a coating substance, an applying member movable in the primary receptacle, a secondary receptacle arranged to receive the coating substance from the primary receptacle, and a chain movable through the secondary receptacle and carrying coating-applying fibers.

11. In a coating-applying apparatus, a receptacle for a coating substance, a work-contacting coating-applying roll rotatable to dip therein and having an upper portion exposed for engagement with work presented thereto, and a coating-ap-

plying brush arranged to contact with and to remove coating substance from the roll.

12. In a coating-applying apparatus, a receptacle for a coating substance, a work-contacting coating-applying roll above said receptacle and dipping therein, a coating-applying brush arranged to remove the coating substance from the roll, and means arranged to vary the relation of the brush to the periphery of the roll thereby to control the quantity removed.

13. In an apparatus for coating articles having opposite beveled edges, means for advancing the articles, coating-applying means acting upon the advancing articles, auxiliary coating-applying means movable transversely of the path of the advancing articles and having oppositely movable portions acting simultaneously upon opposite beveled edges, and means to supply coating material to said auxiliary applying means.

14. In a coating-applying apparatus, means for advancing articles to be coated, coating-applying means acting upon the advancing articles, and auxiliary coating-applying means movable simultaneously in opposite directions transversely of the path of the advancing articles.

15. In a coating-applying apparatus, means for advancing articles to be coated, an endless flexible member movable transversely of the path of the articles, and coating-applying means carried by the endless member.

16. In a coating-applying apparatus, means for advancing articles to be coated, an endless member movable transversely of the path of the articles, a series of rotatable holders carried by the member, and groups of coating-applying fibers mounted in the holders.

17. In a coating-applying apparatus, means for advancing articles to be coated, an endless chain movable transversely of the path of the articles and consisting of links connected by tubular studs rotatable in the links, and groups of coating-applying fibers carried by the studs.

18. In a coating-applying apparatus, a rotatable coating-applying roll, a trough having an opening at one side, said opening being situated in proximity to the applying roll and receiving the coating substance therefrom, and an applying member movable in the trough.

19. In a coating-applying apparatus, a rotatable coating-applying roll, a trough having an opening at one side, said opening being situated in proximity to the applying roll and receiving the coating substance therefrom, the trough being arranged to deliver its overflow above a portion of the roll, and an applying member movable in the trough.

20. In a coating-applying apparatus, a rotatable coating-applying roll, a trough having an opening at one side, said opening being situated in proximity to the applying roll and receiving the coating substance therefrom, mounting means for the trough arranged to permit its position to be varied toward and from the roll, and an applying member movable in the trough.

21. In a coating apparatus, a receptacle for a coating substance, and an applying member movable in the receptacle with its applying portion above the level of the substance therein, there being walls upon the receptacle arranged to gather the coating substance and deliver it to the applying member.

22. In a coating-applying apparatus, a trough for a coating substance generally open at the top but having walls above its ends, and a brush traveling through the trough with the upper ends

of its fibers co-operating with said walls to receive the coating substance therefrom.

23. In a coating-applying apparatus, a rotatable feed member having a series of star-wheels spaced from one another along the axis of rotation, supporting sprockets, and an endless coating-applying brush encircling said sprockets with at least one run of the brush engaging the work at a position opposite that at which it is engaged by the star-wheels, said run of the brush being movable longitudinally of the axis of said feed member.

24. In a coating-applying apparatus, a movable coating-applying brush, a rotatable feed member co-operating with the brush and having a series of star-wheels spaced from one another along the axis of rotation, and means arranged to move portions of the brush simultaneously in opposite directions across the work.

25. In a coating-applying apparatus, a movable member for applying a coating substance, a second movable applying member arranged to receive a supply of the coating substance from the first-mentioned member, and a feed and pressure member co-operating with each applying member.

26. In a coating-applying apparatus, a primary receptacle for a coating substance, an applying member movable in the primary receptacle, a secondary receptacle above the level of the substance in the primary receptacle and arranged to receive the coating substance from the primary receptacle, an applying member movable in the secondary receptacle, and a rotatable feed member situated above each receptacle and co-operating with each applying member.

27. In a coating-applying apparatus, a receptacle for a coating substance, a coating-applying roll rotatable therein, a coating-applying brush arranged to contact with the coating substance upon the roll, a rotatable feed member co-operating with the roll, and a rotatable feed member co-operating with the brush.

28. In a coating-applying apparatus, a receptacle for a coating substance, a movable primary work-coating member receiving the coating substance from said receptacle, a movable secondary work-coating member arranged to receive a supply of the coating substance from the first-mentioned member, and means arranged to move the secondary member in either of two directions.

29. In a coating apparatus, means for advancing articles to be coated, endless, band-like coating-applying means having elongated side portions or runs of flexible applying elements, said runs being movable in opposite directions transversely of the path of the advancing articles, means for imparting a movement of translation to the elongated side portions of the endless coating-applying means, and means arranged to reverse the direction of movement of the endless coating-applying means thereby to prevent a distortion of said applying elements in one direction of deflection.

30. In a coating-applying apparatus, means for advancing articles to be coated, an endless member movable transversely of the path of the articles, a series of rotatable holders carried by the member, groups of coating-applying fibers mounted in the holders, and gearing arranged to move the endless member in either direction across the path of the advancing articles.

31. In a coating-applying apparatus, a receptacle for a coating substance, a movable primary work-coating roll dipping therein, a mov-

able secondary work-coating member arranged to receive a supply of the coating substance from the applying roll, gearing for moving the secondary member in opposite directions, and a shifting member associated with the gearing.

5 32. In a coating-applying apparatus, means for advancing articles to be coated, a band-like, endless work-coating member with opposed runs

having coating-applying fibers for contact with the work and having one of its runs movable transversely of the path of the article, means for supplying coating substance to said fibers, and means for moving said endless member in either of two opposite directions in contact with the articles.

DANIEL ANTHONY SCARNEGIE.

CERTIFICATE OF CORRECTION.

Patent No. 2,051,154.

August 18, 1936.

DANIEL ANTHONY SCARNEGIE.

It is hereby certified that error appears in the printed specification of the above numbered patent requiring correction as follows: Page 2, second column, line 55, for the hyphenated word "bundle-like" read band-like; and that the said Letters Patent should be read with this correction therein that the same may conform to the record of the case in the Patent Office.

Signed and sealed this 6th day of October, A. D. 1936.

Henry Van Arsdale

(Seal)

Acting Commissioner of Patents.
